UNITED STATES PATENT OFFICE.

KENNEDY DOUGAN, OF MINNEAPOLIS, MINNESOTA.

STEAM-PUMP.

1,114,345.

Specification of Letters Patent. Patented Oct. 20, 1914.

Application filed January 16, 1909. Serial No. 472,667.

To all whom it may concern:

Be it known that I, KENNEDY DOUGAN, a citizen of the United States, and resident of the city of Minneapolis, county of Hennepin, and State of Minnesota, have invented certain new and useful Improvements in Steam-Pumps; and I do hereby declare the following to be a full, clear, and exact description of the invention, such as will enable others skilled in the art to which it appertains to make and use the same.

The object of the invention is to provide a single acting steam pump in which the percentage of piston leakage in both steam and water cylinder, will be the same whether the pump is making the maximum or minimum number of strokes per unit of time. It is well known that the loss of steam due to piston leakage is considerable, and since the leakage is in proportion to the time steam is acting on the piston, it follows that the percentage of leakage will be ten times as great when a pump is making one stroke per minute as when making ten strokes per minute.

In the invention herein disclosed, one stroke of the pump, that is the working stroke, is always made at the maximum practicable speed, and the speed of the return stroke, being effected by fluid pressure on a relatively small piston, said fluid pressure being controlled manually by a throttle valve or automatically by a pressure or altitude responsive device, will be at a diminished rate regulable at will.

In the accompanying drawings, Figure 1 is a diagrammatic view, in vertical longitudinal section, of a single acting pump embodying the invention, the steam end being indicated by dotted lines; Fig. 2 is a vertical cross-section on line *a*—*b* of Fig. 1; Fig. 3 shows means for working the pump in one direction by air pressure; Fig. 4 shows means for working the pump in one direction by steam pressure; Fig. 5 is a vertical cross-section on line *c*—*d* of Fig. 4.

In the drawings, the water end of the pump is shown in a special form which is well adapted to the purposes of this invention, but the invention is applicable to other and different pump structures. The steam end of the pump is represented by the cylinder 1, piston 2, supply pipe 46, and throttle 47.

3 is the water piston cylinder, one end of which is open and is connected with a pipe

6. Said pipe may be much longer than shown. At its distant end it is connected to a valve chamber 7, in which are lift valves 8. Said chamber above the valves 8 is connected to a stand-pipe 9 near the bottom thereof. The diameter of the stand-pipe should be not much greater than that of the water cylinder 3.

Connected to the pipe 6 at any point, but preferably adjacent the valve chamber 7, is the induction pipe 11. Pipe 11 approaches pipe 6 on a curve or at an angle, and preferably in a direction toward the water cylinder. Its lower end is enlarged as at 11', and provided with foot-valves 12.

13 is the level of the water supply.

In this pump, the piston 2 is driven in (to the right) by steam pressure, and back by water, air or steam pressure. The arrangement shown in Fig. 1 is for water pressure. As, on account of the valves 8, the said water pressure cannot act on the piston 14, a small separate cylinder 15 is provided, and in it is placed a piston 16 on a rod 17, rigidly connected to piston rod 5 by a member 18. Cylinder 15 is practically coextensive with pipe 6, and terminates in a valve chamber 19 containing valves 20. Above the valves said chamber is connected to the stand-pipe 9 by a connection 21.

Connected around said valves 20 is a bypass 22, in which are a hand-valve 23 and an automatically operated valve 24. The latter has a short crank-arm connected by a rod 26 with a pressure-responsive device 27, (indicated) that is connected by a pipe 28 to the stand-pipe 9. The parts are so adjusted that when there is less than the required pressure in the stand-pipe 9, the valve 24 will be wide open.

The end of the cylinder 3 at which the piston-rod enters is simply bored to fit the piston rod; no packing is necessary. An upwardly extending pipe or chamber 29 is connected to cylinder 3 near the end of the latter. Said pipe or chamber is provided with a pipe 30 open to atmosphere. The function of the chamber 29 is to provide water packing or a water seal for the piston rod and head. Water will accumulate behind the piston 14 through leakage past said piston in its forward stroke. When the chamber becomes filled, water will overflow through pipe 30 and leak around piston rod 105 as fast as it leaks back around the piston 14.

The operation of the water end of the

pump is as follows: Starting with the pistons at the position shown, the hand-valve 23 being open, and there being a head of water in the stand-pipe 9, the water pressure is transmitted through valves 23 and 24 and pipe 22 into the return piston cylinder 15; drives back the piston 16 and with it the main piston rod 5 and pistons 2 and 14. Water is drawn up through the induction pipe 11 into pipe 6 (which is combined induction and eduction pipe) and follows the piston 14. When the end of the stroke is reached, steam is admitted behind piston 2 and drives it quickly in the opposite direction. The steam is admitted behind piston 2 at full pressure, and said piston is driven quickly to the end of its stroke. The steam leakage around the piston is minimized. Water is driven from pipe 6 past the head-valves 8 and enters the stand-pipe 9. The water pressure again drives the pistons to the other end, and so on. During the out stroke the water ahead of the return piston 16 passes partly through pipe 22 and partly through the check valves 20.

The function of the hand valve 23 is to enable the operator to control the speed at which the pump pistons return, thereby controlling the number of beats of the pump per unit of time. This valve may be dispensed with, however, if the delayed valve motion shown in my copending applications Serial Numbers 472,670 and 476,671, filed on even date herewith, on steam pumps be employed. The function of valve 24 is the same as that of valve 23, but it is adapted to be governed by changing pressures in the stand-pipe 9. For example, when the said pressure exceeds a certain amount, the device 27 turns the valve 24 toward closed position; this chokes the flow of water through said valve and causes the pump pistons to return more slowly. This device also may be dispensed with if the above named devices are used on the steam valves of the pump.

The pistons may be returned by the expansion of compressed air confined in a chamber communicating with the return cylinder 15. Such a device is shown in Fig. 3. 32 designates the return cylinder which is closed at 33, and has a port 34 opening into an air-chamber 35. To prevent leakage around the piston 36, a body of water is placed between the piston and the air. 37 is a pipe leading to a source of water under pressure, such as the stand-pipe. Initially, the compressed air is pumped in through an air pipe 38. The operation will be obvious.

The feature of the invention whereby the pistons are actuated in one direction by water pressure works an economy, as it will be obvious that to employ steam pressure in cylinder 1 to return the piston would be a

waste of steam. But steam may be employed for returning the pistons when there is not a sufficient head of water in stand-pipe 9. In my copending applications Serial Numbers 472,670 and 472,671, filed on even date herewith, the steam for this purpose is admitted to the main steam cylinder.

In Fig. 4 of the present drawings, a smaller and separate cylinder 40 is provided, having a piston 41 therein, whose rod 42 is secured to the main piston rod 5, as shown. Cylinder 40 is extended and connected with the valve chamber 19 the same as shown in Fig. 1. In said cylinder, just beyond the end of the stroke of piston 41, a gate valve 43 is placed. A steam pipe 44 is connected to the cylinder 40 at 45, and leads to the steam pipe 46 above the throttle 47. In steam pipe 44 is a check-valve 48, opening in the direction of the arrow. A bypass 49 is connected around the valve 48 and in it is connected a hand-valve 50.

To start the pump when stand pipe 9 is empty, let steam into cylinder 40 through valve 50 which will drive piston 41 and connected parts to the left, and warm up cylinder 40. When the water of condensation has escaped through open valve 52 carried by the pipe 51, said valve is closed sufficiently to only allow the water of condensation to escape. Throttle 47 is then opened and the steam in the steam end of the pump drives the parts forward, the check valve 48 is opened by the steam pressure ahead of piston 41, so the steam does not have to pass backward through valve 50. The pump is thus operated by steam until there is a high enough head of water in the stand-pipe to return the parts without the aid of steam pressure. The steam valve 50 is closed, and the gate 43 is opened.

I claim:

1. A single acting direct acting steam pump, comprising a pumping piston steam-actuated to effect its active or water-forcing stroke at maximum speed, means independent of the steam for returning the piston at diminished speed, and means for regulating the action of said returning means to vary the rate of return.

2. A single acting direct acting steam pump, comprising a pump cylinder, a piston therein steam-actuated to effect its outward or water-forcing stroke, an auxiliary cylinder and a piston therein operatively connected to the pump piston, a stand-pipe into which the water is pumped by both pistons, check valves preventing return of water through the pumping passages, and a separate water connection between the stand-pipe and the auxiliary cylinder at that side of the piston that will actuate said piston in the opposite direction to that of the steam stroke.

3. The combination, with a single acting

direct acting steam pump, of a pump cylinder, a piston and rod therein, an auxiliary cylinder containing a piston, the rod of said piston being operatively connected 5 to the pump piston rod; a stand-pipe into which the water is pumped; a water connection, having check valves therein, between the stand-pipe and the auxiliary cylinder, a bypass around said check-valves; 10 and a regulating valve in said bypass.

4. The combination, with a single acting direct acting steam pump, of a pump cylinder, a piston and rod therein, an auxiliary cylinder containing a piston, the rod 15 of said piston being operatively connected to the pump piston rod; a stand-pipe into which the water is pumped; a water connection, having check valves therein, between the stand-pipe and the auxiliary cylinder; a bypass around said check-valves; 20 a regulating valve in said bypass, a pressure-responsive device operatively connected to said valve, and a water connection between said device and the stand-pipe.

25 5. A single acting direct acting steam pump, comprising a pump cylinder, a piston therein steam-actuated to effect its outward or water-forcing stroke, an auxiliary cylinder and a piston therein operatively connected to the pump piston, means for maintaining a fluid pressure upon said auxiliary piston sufficient to actuate the pump piston in the opposite direction to that of the steam stroke thereof at diminished 30 speed, and means for regulating the action of said fluid to vary the rate of movement of the pistons in the direction opposite the steam strokes.

35 6. A single acting direct acting steam pump, comprising a pump cylinder, a piston therein steam-actuated to effect its outward or water-forcing stroke, an auxiliary cylinder and a piston therein operatively connected to the pump piston, a stand-pipe 40 into which the water is pumped by both pistons, check valves preventing return of water through the pumping passages, a separate water connection between the stand-pipe and the auxiliary cylinder at that side

of the piston that will actuate said piston 50 in the opposite direction to that of the steam stroke, and a regulating valve in said water connection.

7. The combination with a single acting direct acting steam pump, of a pump cylinder, a piston and piston rod therein, an auxiliary cylinder containing a piston, the rod of said piston being operatively connected to the pump piston rod, a stand-pipe into which the water is pumped, a water connection having check valves therein between the stand-pipe and the auxiliary cylinder, a bypass around said check valve, a regulating valve for said bypass, a pressure responsive device operatively connected to said valve, a water connection between said device and a stand-pipe, and a chamber in communication with the pump cylinder at the end at which the piston rod enters, for the purpose specified.

8. The combination with a single acting direct acting steam pump, of a pump cylinder, a piston and piston rod therein, an auxiliary cylinder containing a piston, the 75 rod of said piston being operatively connected to the pump piston rod, a tank, a pipe communicating with the pump cylinder and tank, check valves in said pipe, a pipe connecting the water supply and the 80 pump cylinder, check valves in said pipe and closing in opposite directions from those in the pipes leading from the pump cylinder and the tank, a water connection having check valves therein between the 85 tank and the auxiliary cylinder, a by-pass around said check valve, a regulating valve for said by-pass, a pressure responsive device operatively connected to said valve, a water connection between said device and 90 tank, and a chamber in communication with the pump cylinder at the end at which the piston rod enters, substantially as shown and described.

KENNEDY DOUGAN.
